ASH TRAY

John G. Hoehn, Pennsboro, W. Va.

Application February 24, 1950, Serial No. 8,108

Term of patent 3½ years

(Cl. D85—2)

To all whom it may concern:

Be it known that I, John G. Hoehn, a citizen of the United States, residing at Pennsboro, in the county of Ritchie and State of West Virginia, have invented a new, original, and ornamental Design for an Ash Tray, of which the following is a specification; reference being had to the accompanying drawings, forming a part thereof.

Figure 1 is a top plan view of an ash tray, showing my new design;

Figure 2 is a side elevational view; and

Figure 3 is a sectional view taken along the line 3—3 of Figure 1.

I claim:

The ornamental design for an ash tray, as shown.

JOHN G. HOEHN.
